UNITED STATES PATENT OFFICE

2,550,712

GUN SIGHT CONTROL

William H. Newell, New York, and Lawrence S. Brown, Long Island City, N. Y., assignors to The Sperry Corporation, a corporation of Delaware

Original application May 5, 1944, Serial No. 534,330. Divided and this application March 24, 1945, Serial No. 584,632

9 Claims. (Cl. 33—49)

1

This invention relates to automatic gun control systems of the type in which a gun mount is driven in response to movement of a precessed gyroscope at controlled rates of train and elevation and the gun is automatically given a lead or deflection with respect to the line of sight, both in train and in elevation, which is a function of the range, the speed of the observer and the rates of train and elevation.

This application is a division of the copending application of Newell, Tear and Brown, Ser. 534,330 filed May 5, 1944, which is now abandoned, for Automatic Gun Control System, and relates particularly to the mounting for the sighting and computing mechanism.

An object of this invention is to provide a mechanism of the above type having novel and improved details of construction and features of operation.

Another object is to provide a system of the above type which is suited to production and operation under military conditions.

Another object is to provide a system of the above type which is of wide application to various types of turrets on shipboard, planes, land vehicles, fixed anti-aircraft guns and the like.

Other objects and advantages will be apparent as the nature of the invention is more fully disclosed.

Although the novel features which are believed to be characteristic of this invention are pointed out more particularly in the claims appended hereto, the nature of the invention will be better understood by referring to the following description, taken in connection with the accompanying drawings in which a specific embodiment thereof has been set forth for purposes of illustration.

In the drawings,

Fig. 1 is a vertical section through a gun turret showing the control mechanism in front elevation;

Fig. 2 is a side elevation of the control mechanism shown in Fig. 1;

Fig. 3 is a top plan view thereof;

Fig. 4 is a side elevation of a control box and associated mechanism; and

Fig. 5 is a detail view of the differential mechanism for the range shaft.

Certain specific terms are used herein for convenience in referring to various details of the invention. These terms, however, are to be given an interpretation commensurate with the state of the art.

Referring to Figs. 1, 2 and 3, the mechanism

2

is shown as comprising a pair of guns 10 and 11 carried in cylindrical gun mounts 12 and 13 respectively which are pivoted for movement in elevation about outer horizontal trunnions 14 and 15 respectively and inner horizontal trunnions 16 and 17 respectively. The outer trunnions 14 and 15 are carried by outer brackets 18 and 19 respectively. The inner trunnions 16 and 17 are carried by inner brackets 20 and 21 respectively.

The gun mounts 12 and 13 are adjusted in elevation by means of gears 25 mounted upon an elevation shaft 26 and engaging circular racks 27 on the gun mounts 12 and 13. The elevation shaft 26 carries a gear 28 which is driven by a pinion 29 actuated by a hydraulic motor 30 mounted on a support 32 which extends between the inner brackets 20 and 21. The elevation shaft 26 is mounted in brackets 31 attached to the support 32.

A control box 40 containing the automatic computing mechanism, the gyro-control mechanism and the range finder is mounted on brackets 41 and 42 (Fig. 3), which are journaled in trunnions 43 and 44 respectively carried by the inner frame members 20 and 21. The box 40 is constrained for movement in elevation with the gun mounts 12 and 13 by a pair of linkages comprising links 45 pivotally mounted by pins 46 to the gun mounts 12 and 13 and telescoping into links 47 which are pivoted at 48 to the brackets 41 and 42. The links 45 are latched to the links 47 by pins 49 (see Fig. 4) which may be withdrawn to permit the links 45 and 47 to be separated so as to disconnect the box 40 from the gun mounts 12 and 13. The box 40 is counter-balanced by springs 53 connected between the pins 54 on the brackets 41 and 42 and stationary pins 54a carried by the inner brackets 20 and 21.

Referring to Fig. 4, the pin 49 is shown as mounted in a bracket 50 and held downwardly by a pressure spring 51. The pin is provided with a knob 52 to provide manual means for withdrawing the pins to disconnect the links 45 and 47 as above mentioned.

Referring again to Fig. 1, a pair of control handles 55 are mounted on a horizontal shaft 400, journaled in a bracket 56 which is mounted for rotation about a vertical axis on a block 57 containing the hydraulic pressure control valves for controlling the precessing pressures. The block 57 is mounted on a bracket 58 (Figs. 1, 2 and 3) which is attached to a transverse plate 59 extending between the inner brackets 20 and 21.

The transverse plate 59 also carries a pump

block 60 on which the main motor 61 is mounted and to which valve blocks 62 and 63 are connected. The valve blocks 62 and 63 control the supply of fluid from the pump to the hydraulic elevation motor 30 and to a hydraulic train motor 65 (Fig. 1) driving a gear 66 which cooperates with a rack 67 on a stationary frame ring 68. The train motor 65 is mounted on a bracket 70 which is attached to the frame 71 of the movable turret. The frame 71 supports the outer brackets 18 and 19 and carries across beams 12 which support the inner brackets 20 and 21 and the transverse plate 59. The frame 71 includes an outer annular member 75 carrying rollers 76 which engage in an annular track 77 on the stationary frame ring 68. The train motor 65 causes the entire turret to rotate inside the track 77. A seat 80 for the gunner is mounted on brackets 81, Figs. 2 and 3, attached to the cross-beams 12.

The general arrangement of the apparatus is such that the gunner rotates the handles 55 about a horizontal axis in accordance with variations in elevation to be applied to the sight for causing it to follow the target in elevation and rotates the bracket 56 about its vertical axis in accordance with variations in train which are to be applied to the sight. These rotations of the handles 55 actuate suitable valves within the valve block 57 to generate pressures which are proportional to the amount and rate of movement of the handles 55 in train and in elevation. These pressures are applied to hydraulic control mechanism within the control box 40 as precessing forces to cause the gyroscope to precess in the desired direction and at a rate depending upon the precessing forces. The precessing pressures also actuate the rate input linkages of the automatic computing mechanism within the control box 40.

These precessing forces then cause the gyroscope and the sight which is associated therewith to move in train and in elevation as desired. This movement of the gyroscope in turn actuates the follow-up valve mechanism within the control box 40 to control the valves within the valve blocks 62 and 63 so as to cause the pumps within the pump block 60 to supply fluid at controlled rates to actuate the elevation motor 30 and the train motor 65. The automatic computing mechanism automatically sets into the follow-up valves the proper deflection so that the gun is caused to be displaced from the line of sight in train and elevation the correct amount for causing the projectile to hit the moving target.

The train shaft 95 is driven through bevelled gears 96 by a flexible train shaft 97 which, as shown in Figs. 1 to 4, is located on the outside of the control box 40 and is driven through bevelled gears 98 from a shaft 99 carrying a pinion 100 meshing with the stationary rack 67 on the frame ring 68. The free end of the flexible shaft 97 and the shaft 99 are mounted on a bracket 102 which is attached to the frame 71 of the turret and rotates therewith, so that the train of the turret, which corresponds to the bearing of the gun (B_g), is fed by the shaft 97 into the train shaft 95 of the computing mechanism.

The range is set into the shaft 160 by a range tape 165 which engages a range pulley 166 connected to drive one side of a differential 167. The other side of the differential 167 carries an elevation pulley 168, driven by an elevation tape 169 in a manner to compensate for movement of

the range tape 165 produced by movement in elevation of the box 40.

The range tape 165, as shown in Fig. 4, passes around idler pulleys 198 and engages a pulley 199 which is loosely mounted about the trunnion 44. A second idler pulley 200, which is attached to the first idler pulley 199, is engaged by a belt 201 passing around a belt pulley 202 which, as shown in Fig. 1, is mounted on a bracket 203 carried by the inner bracket 21. The belt pulley 202 is operated by a link 204 which is pinned to the pulley 202 by a pin 205. The link 204 engages a bell crank lever 206 (Figs. 1 and 2) which is mounted on the inner bracket 21 and is actuated by a link 207 attached to a foot pedal 208 in a position to be operated by the foot of the gunner. A pair of foot pedals 208 and 209 are shown in Figs. 1, 2 and 3 which are connected by a shaft 210 and gears 211 to be actuated in opposite directions so that as one foot is elevated the other foot is depressed. In this way an accurate control is obtained as the operation of the foot pedals is not influenced by the jars to which the gunner may be subjected. The range belt 165 is thus operated through the linkages above mentioned by the foot pedals 208 and 209 by an amount which the gunner determines from the range finder included in the mechanism of box 40.

Elevation is fed into an elevation shaft 220 by an elevation pulley 221 actuated by the elevation tape 169. The tape 169 passes around the pulley 222 which is concentric with pivot 48 and is fixed to the link 47 (Fig. 4) to be actuated by pivotal movement of said link.

Although a specific embodiment of the invention has been shown for purposes of illustration, it is to be understood that the invention is capable of various adaptations as will be readily apparent to a person skilled in the art. The invention is only to be limited in accordance with the scope of the following claims.

What is claimed is:

1. In a range computer, a housing mounted for movement in elevation about a transverse horizontal axis and including an adjusting shaft displaced from said axis, an idler pulley mounted for rotation about said axis, transmission means transmitting movement from said pulley to said shaft, a control pedal, a range link actuated by said pedal, and transmission means transmitting movement of said link to said pulley.

2. In a range computer, a housing mounted for movement in elevation about a transverse horizontal axis and including an adjusting shaft displaced from said axis, an idler pulley mounted for rotation about said axis, transmission means transmitting movement from said pulley to said shaft, a control pedal, a range link actuated by said pedal, a pulley actuated by said link, and a belt interconnecting said pulleys for actuating said adjusting shaft in response to movement of said control pedal while permitting said elevational movement of said housing.

3. In a range computer, a housing mounted for movement in elevation about a transverse horizontal axis and including an adjusting shaft displaced from said axis, an idler pulley mounted for rotation about said axis, transmission means transmitting movement from said pulley to said shaft, a control pedal, a range link actuated by said pedal, a second pulley mounted for rotation about a fixed axis, said link being pivoted to said second pulley to actuate the same in response to longitudinal movement of said link, and a belt interconnecting said pulleys for actuating said

adjusting shaft in response to movement of said control pedal while permitting said elevational movement of said housing.

4. In a range computer, a housing mounted for movement in elevation about a transverse horizontal axis and including an adjusting shaft displaced from said axis, an idler pulley mounted for rotation about said axis, a range tape driving said adjusting shaft from said idler pulley, a control pedal, a range link actuated by said pedal, a second pulley mounted for rotation about a fixed axis, said link being pivoted to said second pulley to actuate the same in response to longitudinal movement of said link, and a belt interconnecting said pulleys for actuating said adjusting shaft in response to movement of said control pedal, while permitting said elevational movement of said housing.

5. In a range computer, a housing mounted for movement in elevation about a transverse horizontal axis and including an adjusting shaft displaced from said axis, an idler pulley mounted for rotation about said axis, transmission means transmitting movement from said pulley to said shaft, a control pedal, a range link actuated by said pedal, transmission means transmitting movement of said link to said pulley, and means compensating for the movement of said first transmission means produced by elevational movement of said housing about said axis.

6. In a range computer, a housing mounted for movement in elevation about a transverse horizontal axis and including an adjusting shaft displaced from said axis, an idler pulley mounted for rotation about said axis, a range tape driving said adjusting shaft from said idler pulley, a control pedal, a range link actuated by said pedal, a second pulley mounted for rotation about a fixed axis, said link being pivoted to said second pulley to actuate the same in response to longitudinal movement of said link, a belt interconnecting said pulleys for actuating said adjusting shaft in response to movement of said control pedal, while permitting said elevational movement of said housing, and means compensating for the movement of said range tape produced by elevational movement of said housing about said axis.

7. In a range computer, a housing mounted for movement in elevation about a transverse horizontal axis and including an adjusting shaft displaced from said axis, an idler pulley mounted for rotation about said axis, a range tape driving said adjusting shaft from said idler pulley, a control pedal, a range link actuated by said pedal, a second pulley mounted for rotation about a fixed axis, said link being pivoted to said second pulley to actuate the same in response to longitudinal movement of said link, a belt interconnecting said pulleys for actuating said adjusting shaft in response to movement of said control pedal while permitting said elevational movement of said housing, an elevation tape moveable in response to elevational movement of said housing about said axis, and differential means actuated by said range tape and by said elevation tape to compensate for movement of said range tape produced by said elevational movement so that said

adjusting shaft is responsive only to actuation of said pedal.

8. In a computer, a housing mounted for movement in elevation about a transverse horizontal axis and carrying a range shaft displaced from said axis to set range into said computer, an idler pulley mounted for rotation about said axis, a range tape driving said range shaft from said idler pulley, a second pulley mounted for rotation about a fixed axis, manual control means to actuate said second pulley, a belt interconnecting said pulleys for actuating said range shaft in response to movement of said manual control means, while permitting said elevational movement of said housing, an elevation tape moveable in response to elevational movement of said housing about said axis, and differential means actuated by said range tape and by said elevation tape to compensate for movement of said range tape produced by said elevational movement so that said adjusting shaft is responsive only to actuation of said manual control means.

9. In a mechanical computer, a housing mounted for movement in elevation about a transverse horizontal axis and carrying a range shaft displaced from said axis to set range into said computer, an idler pulley mounted for rotation about said axis, a range tape driving said range shaft from said idler pulley, a control pedal, a range link actuated by said pedal, a second pulley mounted for rotation about a fixed axis, said link being pivoted to said pulley to actuate the same in response to longitudinal movement of said link, a belt interconnecting said pulleys for actuating said range shaft in response to movement of said control pedal while permitting said elevational movement of said housing, an elevation tape moveable in response to elevational movement of said housing about said axis, and differential means actuated by said range tape and by said elevation tape to compensate for movement of said range tape produced by said elevational movement so that said adjusting shaft is responsive only to actuation of said pedal.
